BY *Wm. D. Walker*
ATTORNEY

UNITED STATES PATENT OFFICE.

WILLIAM D. WALKER, OF SACRAMENTO, CALIFORNIA.

SET OF DICE.

Application filed December 14, 1926. Serial No. 154,706.

This invention relates to improvements in dice, such as are provided in sets for various purposes, my principal object being to provide a set of dice having letters on 5 one face, which letters, when the corresponding dice faces all lie in a common plane or face in the same direction, spell one and only one complete word.

I may also arrange the set of dice with 10 letters on different faces thereof so that the letters of any corresponding set of faces spell a complete word. In this case I have provided means for preventing any letter of one face being used instead of the corresponding letter on another face to complete 15 a word, in the event that both or all words contain one or more of the same letter, as frequently happens.

My set of dice is particularly intended to 20 be used in a dice throwing machine such as is shown in my copending application for patent, Serial No. 154,707, filed Dec. 14, 1926, which machine in turn is used in connection with a premium giving system of a store as 25 explained in said application.

A further object of the invention is to produce a simple and inexpensive device and yet one which will be exceedingly effective for the purpose for which it is designed.

These objects I accomplish by means of 30 such structure and relative arrangement of parts as will fully appear by a perusal of the following specification and claim.

In the drawings similar characters of reference indicate corresponding parts in the 35 several views:

Fig. 1 is a perspective elevation of a set of the dice shown as provided with a word-making series of letters on only one face of 40 the set.

Fig. 2 is a similar view of a set of the dice, with letters on different faces and with control numbers to enable the different faces to be identified regardless of the letters.

Fig. 3 is a similar view of a set of the dice showing a modified method of identifying the various dice faces.

Referring now more particularly to the characters of reference on the drawings, and 50 particularly at present to Fig. 1, 1 denotes the dice themselves of the usual cubical form

and six in number as is customary. All but one of the dice faces have the usual "spots" 2 thereon, while the remaining face of each dice has a letter 3 thereon which 55 with the letters of the faces of the other dice form a complete word. This word is preferably that of the name of the store in which the aforementioned system is used or its proprietor.

The dice are permanently installed in a dice throwing machine such as is shown in the above mentioned co-pending application for patent, the result desired being to have the dice when thrown all facing with said 60 letters uppermost.

In Fig. 2 various faces of the different dice 1^a have letters 3^a instead of the usual spots thereon, the letters on each corresponding set of faces spelling a complete word. 70 It frequently might occur however, as shown on the drawing, that the same letters of the words of two separate sets of faces could be interchanged, which would of course increase the probability of either word being 75 "thrown." To avoid the possibility of any such letter being considered as forming a part of the word of the other set of faces, all corresponding faces have small identifying numbers or other symbols thereon as 80 at 4.

The same result is obtained in connection with the letters 3^b on the faces of the set of dice 1^b shown in Fig. 3, by coloring each set of faces distinct from the others, as indicated by the shade lines 5.

With either form of identification means it may be readily ascertained by a glance whether the letters of a word if formed by throwing the dice, all belong to the same 90 set of faces or not.

From the foregoing description it will be readily seen that I have produced such a device as substantially fulfills the objects of the invention as set forth herein.

While this specification sets forth in detail the present and preferred construction, still in practice such deviations from such detail may be resorted to as do not form a departure from the spirit of the invention, 100 as defined by the appended claim.

Having thus described my invention what

I claim as new and useful and desire to secure by Letters Patent is:

A set of dice, different face of each die having letters thereon which, with the letters on corresponding faces of the other dice, form complete and different words, the letters being such that when the dice are arranged to expose the spelling of a pre-

selected word on the top faces of the dice the side and front faces of the dice will expose the spelling of words which will read in sense making continuity with the first words. 10

In testimony whereof I affix my signature.

WILLIAM D. WALKER.
